UNITED STATES PATENT OFFICE

2,212,542

COMPACT ADJUSTABLE BOILER SUPER-
HEATER

William Anthony Jones, Port Richmond, N. Y.

Application February 28, 1938, Serial No. 193,034

4 Claims. (Cl. 122—249)

My invention is a development of the adjustable boiler superheater for which United States Patent No. 1,929,532 was granted to me Oct. 10, 1933, which dominates this.

5 This development occupies less space. Lines 60 to 68 of page 1 of that patent state: "For ratings below that at which the resistance of vapor flow through a foot of height of the coil is less than the pressure due to a foot of 10 height of the liquid, several coils operating in parallel will tend to distribute the flow equally between them and the rate of flow for them all can be determined by the difference in pressure governed by one thermostatic valve."

15 The fact that the resistance of flow, per foot of length of tube, is a function of the density and of the square of the velocity, results in this resistance being very much less for the water heating length and for the evaporating length than 20 for the superheating length of the tube.

This permits more length of tube and more coils per foot of height in the water heating surface and per foot of height in the evaporating surface than per foot of height in the superheating surface. This results in less total height for 25 a given service.

The tubes of two or more concentric helices tend to shield the upper and lower surfaces of the tubes from contact with the hot gas.

Making the center line of one helical coil offset from the center line of another helical coil of any one element, reduces this shielding of the upper and lower surfaces of the tubes except where the tubes cross each other.

35 One right hand helix and one left hand helix may be put together side ways, horizontally, after being formed, and brought to a position where the centers of the helices are the required distance apart, even when the pitch is greater for 40 the vapor heating surface than for the liquid heating surface and for the evaporating surface.

Two right hand helices or two left hand helices of any one element may be formed together at one time and then moved so that their centers 45 are apart, but evidently they can not be put together or taken apart after being formed if the pitch of the water heating surface or the pitch of the evaporating surface is different from 50 the pitch of the superheating surface.

Referring to the accompanying drawings;

Fig. 1 is a vertical sectional view showing the steam drum and float valve, corresponding to Fig. 1 of Patent No. 1,929,532.

Fig. 2 is a view, looking horizontally, showing

an element formed of one right hand and one left hand helix.

Fig. 3 is a sectional view, looking horizontally at 90 degrees from the direction of looking at Fig. 2, also of an element formed of one right hand and one left hand helix, with their centers apart.

Fig. 4 is a view like Fig. 3, but not in section.

Fig. 5 is a part plan view of four elements as described and of the headers to which they connect.

Fig. 6 is a part plan view, partly in section, with single tube helices having more length of tube per foot of height in the lower part than in the upper part, otherwise similar to Fig. 6 of United States Patent 1,929,532.

Fig. 7 is a part plan view, partly in section, with two tube helices with centers offset, and otherwise corresponds to Fig. 7 of United States Patent 1,929,532.

Fig. 8 is a part plan view of four tube helices, alternately right hand and left hand and with their centers offset so that the longitudinal pitch of the overlapping parts of one helix will slope the same as the overlapping part of the helix above and of the helix below, thus permitting a minimum pitch of each helix, about four times the diameter of the tube.

Fig. 9 is an enlarged part plan view of one right hand helix and one left hand helix, otherwise as described for Fig. 8 and permitting a minimum pitch of about two times the diameter of the tube.

Like reference characters indicate like parts in the several views.

In the compact adjustable boiler superheater shown, which I have chosen for purposes of illustration, feed pipe 1 supplies liquid to a float valve 2, maintaining level 3 of liquid in container 4.

A spring 100 may support part of the weight of float valve 2, which must be heavy to be strong enough for present day high pressures.

A horizontal part 5 supplies liquid to headers 6, from which liquid flows to lower ends 8 or 8' of helices 9 or 9'.

Upper ends of helices 9 are connected to headers 11, which discharge into drum 12 at one side of thermostatic valve 13, whose function it is to maintain such a pressure in the steam space 14 at one side of the thermostatic valve 13, above the pressure in the space 15, above the float valve 2, as will cause the level 16 of the liquid in the helical coils to be sufficiently below the level 3 to give the required superheat.

The thermostatic valve 13 is represented as formed of the following parts;

A plate 17 with hub 18 slides on feed pipe 1.

A spring 19 is on the pipe 1 between the hub 18 and a second hub 21 which is attached to the pipe.

A plate 23 is fastened to the shell of the vapor drum 12 by bolts 24.

Circular grooves 25 and holes 26 are formed 10 in plate 17, and circular grooves 27 and holes 28 are formed in plate 23.

With a space 29 between the plates 17 and 23, vapor can pass through the valve from space 14 to space 15.

15 Feed pipe 1, whose temperature is limited to about that of the liquid feed to the boiler does not expand endwise as much as does the drum 12 with increase of temperature, with the result that as the drum grows longer, with increase of 20 temperature, the plate 23 moves with respect to the hub 22, so that at a definite temperature the space 29 between the plates is increased, thus increasing the valve flow area and limiting the difference in pressure to that which will depress 25 the liquid in the coil just enough to give the required superheating surface to give the required superheat.

Feed pipe 1 and hubs 21 and 22 can be moved by differential screw 31, so that with the boiler 30 cold the hub 22 will be at a small distance 32 to the right of the plate 17. Stuffing box 33 permits pipe 1 to be moved without leakage.

Set screws 34 determine the minimum distance between plates 17 and 23 and prevent the 35 complete closing of the thermostatic valve. Lock nuts 35 hold these set screws after they are set.

Nozzle 37 above space 15 of the drum 12, discharges superheater vapor from the boiler.

40 Drum head 38, held by bolts 39, may be removed giving access to the interior of the drum and permitting inner parts of the apparatus to be removed.

U bolts 41 suspend headers 11 from beams 42.

45 Hot gases may flow downward between the helixes or in the reverse direction, but the end of the tube having more length of tube per foot of coil will always be the cooler end, regardless of whether the hot gases flow upwardly or downwardly, because the liquid enters the tube at the 50 end having more length of tube per foot of coil and the superheater is at the end having less length of tube per foot of coil.

55 Valve 55, connected to lower horizontal part 5, may be used for flooding the boiler with liquid and for draining liquid from the boiler.

United States Patent No. 1,929,532, page 2, lines 70 to 74 states;

"Evidently headers 6 can be supported below helical coils, permitting the coils to be drained if desired without other change." 5

That is the construction shown.

Provision is made for container 4 to expand vertically, due to change in temperature, with seal plates 101 where headers 6 pass through the wall of the boiler setting, as shown. 10

I claim:

1. An adjustable boiler superheater having one or more vertical elements each formed of one right hand one left hand helical coil of tube, with their centers offset horizontally, and having 15 more length of tube, per foot of height, in the lower part than in the upper part, as described, surrounded by hot gas and supplied with liquid at the lower end and with the upper end discharging vapor into a space in which the pressure is maintained by a thermostatic valve responsive to the temperature of the vapor discharged in said space, thus depressing the liquid within the coils enough to give sufficient vapor filled surface to give the required outlet temperature of vapor above the boiling temperature. 20

2. An adjustable boiler superheater having one or more helical coils of tube, having more length of tube per foot of length of coil at its cooler end than at its hotter end, surrounded by hot gas 30 and with a thermostatic valve discharging therefrom controlling the relative pressures at the inlet and at the outlet so that only so much liquid is supplied to one end of the coil as will be discharged as vapor of the desired temperature at 35 the other end.

3. In combination, a vertical helical coil of tube, having more length of tube per foot of height in the lower part than in the upper part, to the lower end of which liquid is supplied, hot 40 gas surrounding the coil and imparting heat to it and a thermostatic valve at the upper end of the coil opening at a temperature above that of the boiling liquid.

4. In combination, a float valve part of whose 45 weight is supported independent of its buoyancy, a vertical coil of tube having more length of tube per foot of height in the lower part than in the upper part, receiving liquid from the float valve, hot gas surrounding the coil and a thermostatic valve at the upper end of the coil opening at a temperature above that of the boiling liquid and maintaining a pressure at the outlet of the coil intermediate between that at the float valve and that at the bottom of the coil. 50

55 WILLIAM ANTHONY JONES.
